LINOLEUM RUG OR SIMILAR ARTICLE

Byron R. Parke, New York, N. Y., and Alben J. Milwid, Bayonne, N. J., assignors to Congoleum-Nairn Inc., a corporation of New York

Application July 31, 1952, Serial No. 20,864

Term of patent 14 years

(Cl. D92—17)

To all whom it may concern:

Be it known that we, Byron R. Parke and Alben J. Milwid, both citizens of the United States of America and residents respectively of New York, county of New York, and State of New York, and of Bayonne, county of Hudson, and State of New Jersey, have invented a new, original, and ornamental Design for a Linoleum Rug or Similar Article, of which the following is a specification, reference being had to the accompanying drawing, forming a part hereof, which is a plan view of a linoleum rug or similar article showing our new design. The back of the rug is of a conventional appearance.

We claim:

The ornamental design for a linoleum rug or similar article, substantially as shown and described.

BYRON R. PARKE.
ALBEN J. MILWID.
